Stephen J. Kovacik, Rossford, Ohio, assignor to Libbey-Owens-Ford Glass Company, Toledo, Ohio

Filed Nov. 1, 1960, Ser. No. 62,704

Term of patent 14 years

(Cl. D54—13)

FIG. 1 is a perspective view of a glass cutting tool, showing my new design;

FIG. 2 is a perspective view thereof viewed in the opposite direction;

FIG. 3 is a top view of the cutting tool;

FIG. 4 is a sectional view taken along line 4—4 of FIG. 3; and

FIG. 5 is a sectional view taken along line 5—5 of FIG. 3.

This application is a continuation-in-part of applica-

tion Serial No. D.55,934, filed May 18, 1959, now abandoned.

I claim:

The ornamental design for a glass cutting tool, substantially as shown and described.
